UNITED STATES PATENT OFFICE.

WILLIAM F. H. BRAUN AND EVELYN P. BRAUN, OF WYNNEWOOD, PENNSYLVANIA,
ASSIGNORS TO W. F. HAROLD BRAUN AND THOMAS R. POWELL, TRADING AS THE
DIXIE COMPANY, OF LANSDOWNE, PENNSYLVANIA.

FLOOR WAXER AND POLISHER.

Application filed August 1, 1925. Serial No. 47,414.

To all whom it may concern:

Be it known that we, WILLIAM F. H. BRAUN and EVELYN P. BRAUN, citizens of the United States, residing at Wynnewood, 5 in the county of Montgomery and State of Pennsylvania, have jointly invented certain new and useful Improvements in Floor Waxers and Polishers, of which the following is a specification.

10 The principal objects of the present invention are to provide a floor waxer and polisher which shall present a neat and attractive appearance, which shall be efficient and reliable in use, and which shall be convenient in adjustment for waxing and polishing and for the renewal of waxing and polishing cloths, pads or fabrics. Another object of the invention is to provide simple and reliable mechanism for turning either 15 face of the pad carrier into operative position and for retaining it in that position and for effecting detachment of the pad carrier from the housing. Another object of the invention is to facilitate the application and removal of pads when the pad carrier is detached.

Other objects of the invention will appear from the following description at the end of which the invention will be claimed.

30 In the following description reference will be made to the accompanying drawing forming part hereof and in which—

Figure 1 is a top view with the handle detached.

35 Fig. 2 is a side view with parts broken away.

Fig. 3 is an end view.

Fig. 4 is a bottom plan view with parts broken away.

40 Fig. 5 is a sectional view taken on the line 5—5 of Fig. 4.

Fig. 6 is a perspective view of one of the parts detached, and

45 Fig. 7 is a sectional view showing a detail of construction.

Referring to the drawing, 1 is a housing of the general form of a hollow semi-cylinder, and it is provided with ears 2 and with a stop 3. 4 is a handle pivotally connected 50 with the ears and co-operating with the stop. As shown the handle consists of a wooden bar mounted in a socket 5. 6 is a generally rectangular open ended pad carrier and it is adapted to turn in the housing and

to be connected therewith and disconnected therefrom. The pad carrier has applied to its respective faces a pad or cloth, omitted for clearness of illustration, and the pad on one face is a waxing pad and the pad on the other face is a polishing pad. There 60 are end bars 7 and 8 movable in respect to the ends of the pad carrier. As shown each end bar is adapted to engage the pad carrier walls at their ends and to afford clearance as at 9, Fig. 5, at their sides. The 65 clearance 9 affords space for the pad. As shown each bar is notched at its end as at 10 to receive the side wall of the pad carrier. However, that construction is not essential in all cases. The bar 8 is provided with a 70 pivot 11 adapted to turn in and to be withdrawn from the bearing 12 provided on one end wall of the housing. The bar 7 is provided with a keyway 13, Fig. 5. 14, Fig. 6 is a key. There is a fitting 16 on or in the 75 end wall of the housing, and this key 14 is mounted in that fitting 16 so as to be turnable for turning the pad carrier and endwise movable for connecting with and disconnecting the pad carrier from the housing. The bolt 15 of the key co-operates with the keyway 13 to pivotally support the pad carrier in the housing and to turn the pad carrier in the housing and to disengage the pad carrier from the housing 80 and to connect it therewith. 17 is a spring and to press the key endwise so that its bolt will tend to engage the keyway 13. Lock mechanism is provided for the key. It comprises a projection 18 on the key and 85 a pair of confronting angularly disposed notches of which one, 19, is vertical in Fig. 4, and of which the other, 20, is horizontal in Fig. 4, and between the elements or bodies in which these notches are formed there is 90 space indicated at 21 which provides whatever clearance is required. Normally the projection 18 is seated in the slot 20 and the bolt 15 is seated in the keyway 13, so that the pad carrier is locked in the position 95 shown in Fig. 5. The key may be shifted bodily toward the right in Fig. 4 far enough to clear the notch 20, but not far enough to enter the notch 19, and then turned with the result that the pad carrier is also turned. In that way the waxing or polishing surface 100 of the pad carrier may be presented for use with the pad carrier held against rotation

by engagement of the projection 18 with the slot 20. When the key is shifted far enough toward the right in Fig. 4 to enter the slot 19, the bolt 15 is out of engagement 5 with the keyway 13, so that the pad carrier can be detached from the housing by pulling its pivot 11 clear of the bearing 12.

The pad carrier 6 may have its end bars 8 hinged at one of their ends, as shown in 10 Fig. 7, for convenience, in which case the opposite ends may be secured in closed position by a spring 22 operable from the outside by means of a button 23.

It will be obvious to those skilled in the 15 art to which the invention relates that modifications may be made in details of construction and arrangement and in matters of mere form without departing from the spirit of the invention which is not limited 20 to those matters or otherwise than as the prior art and the appended claims may require.

We claim:

1. A floor waxer and polisher comprising 25 a hollow housing of the general form of a semi-cylinder provided with ears and a stop, a handle pivotally connected with the ears and co-operating with the stop, a generally rectangular open ended pad carrier adapted 30 to turn in the housing and to be connected and disconnected therewith, end bars movable in respect to the ends of the pad carrier and adapted to afford clearance at their sides and of which one is provided with a

pivot element adapted for co-operation with 35 a pivot element provided on one end wall of the housing and of which the other is provided with a keyway, a spring pressed turnable and endwise movable key provided 40 at the other end wall of the housing and adapted to detachably engage the keyway, and lock mechanism for the key comprising 45 a projection on the key and a pair of confronting angularly disposed notches adapted to co-operate with the projection and provided at the last mentioned end wall of the housing.

2. A floor waxer and polisher comprising a hollow housing of the general form of a semi-cylinder, a handle connected with the 50 housing, a generally rectangular open ended pad-carrier adapted to turn in the housing and to be connected and disconnected therewith, end bars movable in respect to the ends of the pad carrier and adapted to afford 55 clearance at their sides, a pin and bearing in separable relation arranged between one of said bars and the adjacent end wall of the housing, a spring pressed endwise movable and turnable key arranged between the other 60 of said bars and the adjacent wall of the housing and adapted by endwise movement to connect and disconnect the housing and bar, and lock mechanism adapted to permit the key to turn the pad carrier and to lock it 65 in either of two positions.

WILLIAM F. H. BRAUN.
